ADVERTISING DISPLAY STAND

Selig J. Smith, Monterey Park, and Ben Mayer, Los Angeles, Calif., assignors to Kwikset Locks, Inc., Anaheim, Calif., a corporation of California

Application November 4, 1954, Serial No. 32,963

Term of patent 14 years

(CL. D80—9)

To all whom it may concern:

Be it known that we, Selig J. Smith and Ben Mayer, have jointly invented a new, original, and ornamental Design for Advertising Display Stand, of which the following is a specification, reference being had to the accompanying drawing, forming a part hereof.

Fig. 1 is a front elevational view of an advertising display stand showing our new design;

Fig. 2 is an end elevational view;

Fig. 3 is an end elevational view; and

Fig. 4 is a sectional view taken on the broken line 4—4 of Fig. 1.

We claim:

The ornamental design for an advertising display stand, as shown.
